PISTOL GRIP SWITCH

Bobbie Lee Tevebaugh, Danville, Ill., assignor to Duff-Norton Company, Pittsburgh, Pa.

Application June 2, 1958, Serial No. 51,143

Term of patent 14 years

(Cl. D26—1)

Fig. 1 is a perspective view of a pistol grip switch, showing my new design;

Fig. 2 is a side elevational view, the opposite side being substantially a mirror image thereof;

Fig. 3 is a front elevational view; and

Fig. 4 is a top plan view thereof.

The broken line fragmentary showing of a control cable, legible matter and operator's hand is for illustrative purposes only.

I claim:

The ornamental design for a pistol grip switch, as shown and described.
